1 Claim

ABSTRACT OF THE DISCLOSURE

A pump pressurizes the heated hot sump distillate in the distillation process, distilland heating with hot distillate, thus leading to the reduction of overhead clearance requirements for the distiller.

This invention is an improvement to the distillation process, distilland heating with hot distillate. A pump pressurizes heated hot distillate to prevent vapor formation in the liquid. This eliminates the requirement that the liquid level in the condenser sump be elevated above the liquid level in the stratification column.

An object of the invention is the separation of a distillate from a solution.

An object of the invention is the reduction of the overhead clearance requirement for the distiller.

The figure is a flow diagram illustrating the invention.

Referring to the figure, temperature stratification column 50 is a tall vessel containing distillate tubes 98. The vessel and liquid contents have been preheated so that the top is hot and the bottom is cold. Then cold feed solution 9 is fed into the bottom of the column by solution pump 21. In the space surrounding the tubes cold feed solution 9 mixes into concentrated solution 11. The solution rises very slowly, being heated by the tubes. Vapor 4 separates from the solution at liquid surface 3. Part way up the column concentrated solution 11 is discharged. Vapor 4 passes from the column to condenser 51 and is condensed by direct contact with spray distillate 12.

Spray distillate 12 is a mixture of cold distillate 5 and hot sump distillate 6. It is sprinkled into the vapor space of condenser 51 through spray openings 86. Recirculating pump 23 maintains the flow of spray distillate through the spray openings sufficient to keep the temperatures of hot sump distillate 6 and vapor 4 nearly the same. Splash deflector 84 confines the turbulence caused by the falling spray to the top of the condenser sump.

A portion of the flow of hot sump distillate 6 is drawn off by heater pump 26 and fed through distillate heater 53. From the heater heated hot sump distillate 14 flows into the tops of distillate tubes 98. Heater pump 26, in combination with flow restriction 73 pressurizes heated hot sump distillate 14 to prevent vapor formation in the liquid.

Distillate flows very slowly downward inside distillate tubes 98 to distillate box 96. Downward velocities are kept very low so that a large temperature drop is realized by the descending distillate. Cold distillate 5 flows to three-way control valve 63. Three-way control valve 63 alternately directs the flow of cold distillate to the bottom of the condenser sump and to spray openings 86 in the top of the condenser. Small distillate pump 25, pumping a little slower than the flow of cold distillate to three-way control valve 63, takes suction from the bottom of

2

the condenser sump. Cold distillate from small distillate pump 25 continuously mixes with hot sump distillate 6 and flows as distillate mixture 7 to the suction of recirculating pump 23. With this arrangement, cold distillate alternately flows into and out of the bottom of the condenser sump.

Pressure controller 68 has high and low pressure set points, where the control actions reverse. During pressure rise, the controller remotely operates three-way control valve 63 to direct the cold distillate flow to the bottom of the condenser sump. At this time the flow of distillate mixture 7, alone, has insufficient cooling capacity to condense all of the flow of vapor 4. During pressure drop, pressure controller 68 remotely operates three-way control valve 63 to direct the cold distillate flow to spray openings 86 at the top of condenser 51. At this time the flows of distillate mixture 7 and cold distillate 5, together, have more cooling capacity than necessary to condense the flow of vapor 4.

Liquid level controller 66 senses increases in the quantity of distillate in the system at liquid surface 15. It corrects for these increases by remotely operating two-way control valve 61 to release product distillate 8 from the distiller. Liquid level controller 67 senses increases in the level of liquid surface 3. It corrects for these increases by remotely operating two-way control valve 62 to release concentrated solution 11 from the distiller.

Energy 10 is added to the system at a constant rate by the distillate heater 53 and pump motors. Energy is lost by heat carried away with the concentrated solution, by heat carried away with the product distillate and by heat transmission through walls of vessels and piping. Insulation 55 minimizes heat transmission through walls.

Referring to the figure, total energy in the system is controlled by temperature controller 69, which has high and low temperature set points, where control actions reverse. During temperature rise, the controller remotely operates flow control 64 to reduce the flow of cold feed solution 9. This causes a reduction in the flow of concentrated solution 11 through two-way control valve 62 and consequently a reduction in heat being lost from the system. During temperature drop, temperature controller 69 remotely operates flow control 64 to increase the flow of cold feed solution 9. This causes an increase in the flow of concentrated solution 11 through two-way control valve 62 and consequently an increase in heat being lost from the system.

What is claimed is:

1. A distiller for separating distillate from a solution including the following: means flowing cold feed solution into the bottom of the space surrounding a vertical distillate tube in a temperature stratification column, cold feed solution mixing into cool concentrated solution in said space; said distillate tube heating said concentrated solution; means passing concentrated solution from the temperature stratification column at an elevated position out of the distiller; means separating vapor from concentrated solution at its liquid surface in said temperature stratification column; means passing vapor from said temperature stratification column to the vapor space in a vertical condenser chamber having a sump in its lower portion; hot sump distillate accumulating in the upper part of said condenser sump; means permitting hot sump distillate to pass through a distillate heater and

leaving as heated hot sump distillate; means passing said heated hot sump distillate to the top of said distillate tube; a pump pressurizing said heated hot sump distillate to flow as indicated; said heated hot sump distillate being cooled as it descends in said distillate tube and exiting as cold distillate; conduit means conducting said cold distillate from said distillate tube bottom to the lower part of said condenser sump and to vapor contacting means in said vapor space in said condenser; means withdrawing cold distillate from said lower part of said condenser sump and feeding it to said contacting means in said vapor space in said condenser; further conduit means passing cold distillate from the first mentioned conduit as product distillate; a restriction orifice in the first mentioned conduit means conveying the cold distillate exiting from said distillate tube; said pumps and said restriction orifice cooperating to pressurize said heated

hot sump distillate to prevent vapor formation in the liquid.
